CLAIM

The ornamental design for a case for portable electronic computing device, as shown and described.

DESCRIPTION

FIG. 1 is an exploded front perspective view of a case for portable electronic computing device showing my new design.

FIG. 2 is an exploded right elevational view thereof.

FIG. 3 is a rear elevational view thereof.

FIG. 4 is a front elevational view thereof.

FIG. 5 is an exploded left elevational view thereof.

FIG. 6 is an exploded top plan view thereof; and,

FIG. 7 is an exploded bottom plan view thereof.

The features shown in broken lines in the drawing figures depict features that form no part of the claimed design.
